UNITED STATES PATENT OFFICE.

FRANK F. KNOTHE, OF RIDGEWOOD, NEW JERSEY, ASSIGNOR TO KNOTHE BROTHERS, A CORPORATION OF NEW YORK.

GARTER.

No. 860,487.

Specification of Letters Patent.

Patented July 16, 1907.

Application filed May 9, 1907. Serial No. 372,826.

To all whom it may concern:

Be it known that I, FRANK F. KNOTHE, a citizen of the United States, residing at Ridgewood, Bergen county, New Jersey, have invented certain new and useful Improvements in Garters, of which the following is a full, clear, and exact description.

My invention relates to garters which are worn below the knee, and has for its object to provide a new and improved garter easily adjustable as to size and shape, and comfortable to the wearer. Also a garter which has improved ventilation and is easily applied and has other advantages in construction and manufacture.

The garter may be made of leather or of woven fabric, and can be buckled or otherwise secured around the leg.

15 The following is a description of my invention, reference being had to the accompanying drawing, in which

Figure 1 shows the garter extended. Fig. 2 shows the garter as it is when in use.

20 Referring more particularly to the drawings A A' A² are a plurality of members making up the body or strap portion of the garter, the end portions being provided with suitable fastening devices, such, for instance, a buckle B and a perforated tongue C. The several sections of the body are secured together by lacings D D', there being preferably at least three holes in each of the 25 opposing ends for the lacing. These lacings can be loosened or tightened so as to extend the garter as desired. They also provide ventilation at the points at which they occur. The lower portion of the cord forming the lacing D is connected to any suitable hose 30 supporter, such, for instance; as a spring clasp E, by which the stocking F is engaged. I preferably, though not necessarily, have the ends of the cord at the bottom of the lacing and secure them to the supporter as shown.

As above stated, the size of the garter can be varied by simply lengthening the cord in the lacing. Moreover, as the garter is applied, the lacing D, by reason of 40 the extra length, permits the garter to extend automatically, and when the supporter is pulled down by the stocking or in the act of securing it to the stocking, the garter tightens upon the leg. If any strain comes 45 upon the band of the garter, the stocking, yielding somewhat, is drawn up thereby and the garter itself will therefore extend. The garter is not only ventilated directly beneath both of the lacings, but the portion which leads to the supporter consisting of two strands, is 50 ventilated and much cooler than the solid tab which heretofore has been used in connection with leather garters. The body of the garter may be made of leather or woven fabric, and may be elastic or non-elastic. The cords for the lacings may also be elastic or non-

elastic. When leather is used for the body of the garter, I preferably use metallic eyelets G, to reinforce the 55 leather and also to afford a smooth surface, so that the lacings D may more readily slip through the openings. Heretofore the strap surrounding the leg when made of leather has always been cut from one piece. This strap when of one piece has to be curved in form so as to 60 set properly when in use. The cutting of this curved strap in one piece is a great disadvantage in manufacture, since it requires a large piece of leather and results in a very considerable waste. With my garter small pieces of leather can be used and there is practically no 65 waste at all. In order to make the garter set better, I slant the opposing ends a little, so that when the garter is in use the edges of these opposing ends will be substantially parallel. This prevents any overlapping of the portions at that point and also adds to the appearance of the garter when in use.

If desired, the lacing D' may be omitted, the parts A' A² being then formed from a single strip of leather, still leaving a plurality of parts in which case the adjustability in the body of the garter is all secured at the 75 lacing D. If the lacing D' is retained the garter can be adjusted for length at that point, and some of the advantages of my invention thereby retained, even though the lacing D is not used, and the supporter is secured to the body in some other manner. The lacing 80 D securing the supporter is, however, of decided advantage, in that the supporter can be pulled down a considerable distance in attaching the garter to the stocking without unduly contracting the leg, and by the slight expansion of the leg will be automatically raised 85 so as to hold the stocking taut, and the other advantages above referred to will also be secured.

What I claim is:

1. In a garter, the combination of a plurality of parts constituting a strap portion adapted to surround the calf of the leg of the wearer, said parts having opposing ends, each of which is provided with a plurality of openings for a lacing, and a lacing passing through said openings and crossing the space between said ends a plurality of times, a supporter secured to the lower portion of said lacing and carried thereby, and means for temporarily securing the free ends of the strap portion together.

2. In a garter, the combination of a plurality of parts constituting a strap portion adapted to surround the calf of the leg of the wearer, said parts having opposing ends, each of which is provided with three openings for lacing, and a lacing passing through said openings and crossing the space between said ends a plurality of times, a supporter secured to the lower portion of said lacing and carried thereby, and means for temporarily securing the 105 free ends of the strap portion together.

FRANK F. KNOTHE.
